UNITED STATES PATENT OFFICE.

EDWARD P. EASTWICK, OF NEW YORK, N. Y.

APPARATUS FOR REVIVIFYING BONE-BLACK.

SPECIFICATION forming part of Letters Patent No. 293,430, dated February 12, 1884.

Application filed November 1, 1883. (No model.)

To all whom it may concern:

Be it known that I, EDWARD P. EASTWICK, of the city, county, and State of New York, have invented a new and Improved Apparatus for Revivifying Bone-Black, of which the following is a full, clear, and exact description.

The ordinary process of revivifying bone-black after it has lost its effectiveness from use consists in first thoroughly washing the bone-black in water, drying it, and then reburning it in retorts out of contact with air.

The apparatus in general use for reburning the bone-black consists of a number of vertical retorts placed in a kiln, which retorts pass through the top and bottom of the kiln. At the top the retorts receive the bone-black, which, after being subjected to high heat, passes out at the bottom into sheet-iron coolers exposed to the open air; and often there is placed over the kiln containing the retorts an apparatus for drying the bone-black before it enters the retorts by heat obtained from the waste gases from the kiln, thus effecting a saving in fuel.

My invention seeks to effect a still further saving in fuel; and it consists, first, in utilizing the heat given off from the bone-black coolers, and, secondly, in utilizing the heat contained in the heated air that has been passed through the bone-black in the drier.

Reference is to be had to the accompanying drawings, forming part of this specification, in which similar letters of reference indicate corresponding parts in all the figures.

Figure 1 shows, in sectional elevation, taken on the line *x-x* of Fig. 2, a combined bone-black drier and kiln embodying the principles of my invention. Fig. 2 is a sectional side elevation of the same, taken on the line *y-y* of Fig. 1; and Fig. 3 is a sectional plan view taken on the line *z-z* of Fig. 1.

The bone-black kiln A, retorts B, placed therein, coolers C, and the valves D at the bottom of the coolers, are of the ordinary construction.

Around the coolers C are placed the boxes E, to which a forced current of air is supplied from blower F through pipe G and one or more branch pipes, H.

Leading from the boxes E are the pipes I, which come together at I' outside of the kiln,

and connect with the pipes L, placed in the chamber J, through which the products of combustion from the kiln pass on their way to the chimney through the pipe K.

Upon the walls which inclose the chamber J is placed the bone-black drier M, which in this instance is constructed with the central air-passage, N, and side triangular air-passages, O, into which latter passages the pipes L discharge hot air through the side pipes, P, and valved openings f. The central air-passage, N, is closed at the top and connected, through opening N' and pipe Q, with the tortuous pipe R, placed in the box S, situated immediately in front of the blower F. The side walls of the central air-passage, N, are perforated, as shown at a, and over these perforations are secured the inclined plates d, which, together with the triangular passages O, form the irregular drying-spaces G' G', to which the bone-black, after being washed, is admitted and held in thin columns. The heated air forced into the passages O passes out from said passages through the openings c. Thence the hot air passes through the thin columns of bone-black into the central passage, N, through openings a, absorbing and carrying with it the moisture contained in the bone-black. From the central passage, N, the hot air, after passing through the bone-black, passes through the pipe Q and tortuous pipe R, and exhausts into the open air at g. The tortuous pipe R is connected at its lower folds with the pipe T, for conducting away water and other matter that may condense in the pipe R; and in the box S are placed the space-plates h, for deflecting the current of air from the blower F, for bringing it in contact with all parts of the pipe R.

The working of the apparatus is as follows: A force of air created by the blower F passes into and through the box or receiver S, and during its passage extracts the heat of the hot air and vapor passing through the condensing-pipe R. Thence the warm current of air passes through the pipes G H into the lower part of the cooling box or boxes E and around the bone-black coolers C, therein inclosed, to the pipes I at the upper part of the said box or boxes. In passing over and around the coolers C the air absorbs a large portion of heat

from the bone-black in the coolers. From the pipes I the current of air continues on through the pipes L (where it becomes highly heated) to the bone-black drier M, where it passes 5 through the bone-black and evaporates the moisture contained in the wet bone-black. The current of air passes thence, carrying with it the vapor formed, through the pipe Q, to the condensing pipe R, where the vapor is 10 condensed, the heat therein contained being absorbed by the current of air entering the box or receiver S, and the air is discharged at the end of the condenser into the open air at g.

The advantages which this process possesses 15 over any now or heretofore used and the improvements thereby effected are, that a large portion of the heat which, by the ordinary methods of revivifying bone-black, is lost, is herewith reclaimed for useful purposes—viz., 20 the heat which is radiated by the coolers into the open air, and the heat of vaporization in the drying of the bone-black, which is absorbed by the air-current when the latter enters the box or condenser S, after leaving the 25 blower—and the excessive heating up of the kiln-house by radiated heat and vapor is avoided. The current in the cooler box or boxes E may be diverted by partitions set in the same in such manner as may be desired. 30 The box or condenser S and cooler box or boxes E need not both be used in one combination, but may be separately applied—the

condenser with the drier and the box or boxes E with the drier—and the air heated may be used for other purposes than drying the bone-black, if desired. 35

Having thus fully described my invention, I claim as new and desire to secure by Letters Patent—

1. The combination, with the bone-black 40 coolers C, of a casing surrounding the coolers for confining a current of air in contact with the coolers, substantially as and for the purposes set forth.

2. The pipe R, placed in box S, and connected with the drier M by pipe Q, in combination with the blower F, boxes E, and pipes G H, all arranged to operate substantially as and for the purposes set forth. 45

3. The casing E, surrounding the coolers C, 50 and connected through suitable pipes with the drier M, in combination with an air-forcing device connected with the casing E, substantially as and for the purposes described.

4. The box or condenser S, connected with 55 the drier M by suitable pipes, in combination with the blower F, connected with said box, and the pipe R, placed in the box, and connected with the drier M by pipe Q, substantially as and for the purposes set forth.

EDWARD P. EASTWICK.
